PIPE SUSPENDING DEVICE

Marvin R. Jones, Houston, Tex., assignor, by
mesne assignments, to Standard Oil Develop-
ment Company, Elizabeth, N. J., a corporation
of Delaware

Application January 6, 1949, Serial No. 69,533

4 Claims. (Cl. 166—1)

1

This invention relates to new and useful improvements in pipe-suspending devices and relates particularly to devices for suspending and supporting tubular conductors, such as casing and tubing, within a borehole.

In the drilling of wells for oil, gas and other fluids, it is the general practice to employ casing or pipe to line the walls of the borehole, with successive inner casing strings of gradually diminishing diameter being run in as drilling proceeds. Ordinarily as in land drilling, the well bore initially traverses a competent formation having sufficient strength to give lateral support to the outermost casing string and said outer casing is usually cemented within said formation. Because the competent formation extends substantially to the surface of the borehole and therefore, substantially to the upper end of the casing, said casing has sufficient lateral reinforcement throughout its length to effectively support the weight of the inner casing or pipe strings which are suspended from its upper end thereof through the usual casing and tubing head arrangements at or near the derrick floor.

However, in the drilling of wells at sea or offshore, such as on the continental shelf in the Gulf of Mexico, off coastal Louisiana and Texas, the drilling operation is carried on over water of substantial depth. The borehole initially traverses the formation at the bottom of the ocean and this initial formation is largely of a mucky nature and of insufficient mechanical strength to impart the necessary or required lateral reinforcement or support to the outer casing. Thus, the first competent underground formation traversed by the borehole is located a considerable distance below the derrick floor and upper end of the outer casing so that when the outer casing is cemented or anchored in said competent formation, the point of anchorage of said casing is spaced well below the extreme upper end of the casing. The upper portion of the casing which is extending through the upper incompetent formation and through the water is substantially unsupported laterally and is, in effect, a relatively long slender column which is obviously unstable. In addition, this unstable portion extending through the water and air to the derrick floor which may be as much as 50 feet above the level of the sea is subjected to wave action which imposes considerable lateral loads thereon which further impairs this upper portion as a supporting medium. Therefore, in marine drilling or in the drilling of a borehole where said borehole initially traverses an incompetent zone or forma-

2

tion, it is not practical to suspend or transfer the weight of the inner string of casing or pipe to the outer casing at the upper end of said outer casing through the usual casing and tubing head arrangements because of the instability, due to lack of lateral support, of said outer casing.

To effectively transfer the weight of the inner pipe or casing string to the outer casing and then to the competent formation, it is necessary to locate the point of suspension of the inner string at an elevation within the outer casing where said outer casing has sufficient strength to transfer the load to the formation. In marine drilling the initial formation below the ocean floor does not always impart the required lateral support although it may give some lateral reinforcement to that portion of the outer casing which extends therethrough. Thus, although it is probably preferable to locate the point of suspension of the inner string substantially opposite the competent formation to which the outer casing is anchored, said point of suspension may, in certain instances, be at an elevation above the competent formation. As the casing has sufficient strength at any selected point to effectively transfer the load to the competent formation, the inner pipe string may be suspended within said casing at that point. Since the point or elevation of support or suspension of the inner string is variable, the suspending means or device for said string must be capable of setting at a selected level; also, because the inner string is usually cemented or anchored at its lower end, the suspending device must be capable of being set without rotation or manipulation of the inner pipe string and for this reason, the usual hanger or slip-type supporting devices now in general use, are not applicable or satisfactory for supporting the inner string.

It is, therefore, one object of the present invention to provide an improved device for efficiently suspending or supporting a pipe string within an outer pipe string at a desired level or elevation therein, which device is adapted to be actuated or moved into a set position without the necessity of rotating or otherwise manipulating the pipe string which it supports.

An important object of the invention is to provide an improved hanger device for suspending an inner pipe string within an outer pipe string which is adapted to operate within the annular space between said pipe strings, said device being actuated by hydraulic means controlled from the surface, whereby the device may be selectively set at any predetermined level or

elevation without manipulation or rotation of the inner pipe string.

Another object of the invention is to provide an improved hanger device of the slip-type, which will effectively transfer the weight of an inner pipe string to an outer pipe string, whereby said outer string may transfer the load to a competent sub-surface formation to which said outer string is anchored.

A particular object of the invention is to provide a hanger device, of the character described, which is so constructed that normal circulation downwardly through the inner string and upwardly through the annular space exteriorly of said strings may be carried out past the device, whereby a reversal of the circulation downwardly through the annulus functions to actuate the device to suspend or support the inner string within an outer pipe string.

Still another object of the invention is to provide an improved hanger device which is directly connected in the inner pipe string and which has its gripping members normally restrained from movement into actuating position, together with hydraulically operated means for releasing the restraining means, whereby said gripping members may be operated and moved into actuating position to support or suspend the inner pipe string.

The construction designed to carry out the invention will be hereinafter described together with other features of the invention.

The invention will be more readily understood from a reading of the following specification and by reference to the accompanying drawings, wherein an example of the invention is shown, and wherein:

Figure 1 is a longitudinal sectional view of a well bore drilled under the ocean and illustrating the improved hanger device supporting an inner pipe string.

Figure 2 is a view, partly in section and partly in elevation of the hanger device and showing the gripping slips in a retracted position.

Figure 3 is a similar view, with the slips in their expanded or gripping position.

Figure 4 is a horizontal, cross-sectional view, taken on the line 4—4 of Figure 2.

Figure 5 is an enlarged, sectional detail, taken on the line 5—5 of Figure 2, and

Figure 6 is an enlarged sectional detail, taken on the line 6—6 of Figure 2.

In the drawings, the numeral 10 designates a well bore which has been drilled below the ocean floor and which, as illustrated, first traverses an incompetent structure or sub-surface formation A and then traverses a competent structure or formation B. The outer or surface casing 11 extends downwardly from the derrick floor 12 and obviously extends through the water and then through the incompetent structure A, with its lower end projecting into the competent formation B and being cemented therein as indicated at 13. Obviously, the upper portion of the casing which extends through the water is subjected to lateral stresses occasioned by the wave action, and this portion of the casing is completely without lateral support. The incompetent structure A is usually of a mucky formation and although it might provide some lateral support for the casing 11, it is not sufficient to reinforce that portion of the casing to the point where vertical loads may be safely imposed thereon. The point of anchorage of the casing 11 is at the cement 13 opposite the competent formation

B, and this point is a considerable distance from the extreme upper end of said casing, with the result that the entire upper portion of the casing above the competent structure does not have any appreciable lateral support. For this reason, it is not practical to attempt to suspend an inner casing from the extreme upper end of the casing 11 as is the usual practice in land drilling.

In carrying out the present invention, the improved hanger device indicated at H in Figure 1 is connected in the inner pipe or casing string 14 and, as will be explained, is adapted to be set at a desired point within the outer casing 11 to effectively support or suspend the inner string. As illustrated, the device H is locked at a level or elevation substantially opposite the competent formation so that the load or weight of the inner casing 14 is transferred through the device to the outer casing 11 at a point where said outer casing may effectively transfer that load to the formation B which is competent to carry the same. It is pointed out that the device H may be selectively set at any desired point or elevation within the outer string, provided that the casing at such point has sufficient strength to effectively transfer the load to the competent formation. The annular space between the inner and outer casings is sealed off or closed at the surface by a suitable sealing means which is shown schematically and indicated at 15 in Figure 1.

The improved device comprises an elongated tubular mandrel 20 having an axial bore 21 extending entirely therethrough. The mandrel has its upper and lower ends externally threaded whereby it may be connected by means of coupling collars 22 in the inner pipe string 14. The coupling collars are preferably provided with radial projections or guide wings 23 which function to center the mandrel within the outer string and the vertical spaces 24 between the projections or wings form fluid by-pass channels to permit passage of fluid past said couplings. The intermediate portion of the exterior surface of the mandrel 20 is formed with a plurality of tapered expanding surfaces or cones 25. Above the uppermost expanding surfaces 25, the exterior surface of the mandrel is reduced as indicated at 26 whereby an external annular shoulder 27 is formed on said mandrel. Above the surface 26, the mandrel is further reduced as indicated at 26.

A plurality of arcuate slip segments 28 are mounted on the mandrel and are adapted to contact with the slip expanding cones. Any desired number of segments may be employed and four of such segments are shown. Each segment is of sufficient length to extend throughout the expanding surfaces 25 of the mandrel and said segment has its rear surface provided with tapered sections 29 which are complementary to the tapered expanding surfaces 25. The segments are retained in position on the mandrel by flanged retaining clamps 30 which are secured to the mandrel between the longitudinal edges of adjacent slip members by cap screws 31. As is clearly shown in Figure 4, the flanges of the clamps overlie longitudinal ribs or projections formed at each longitudinal edge of each slip segment. The clamps are so positioned that the slip segments or members may undergo a limited outward or radial movement when said segments are moved longitudinally with respect to the expanding surfaces 25 of the mandrel; however, it will be evident that the clamps prevent complete outward displacement of the slip segments from

the mandrel. Each slip segment is provided with longitudinal grooves or recesses 33 which permit a by-pass of fluid past the segments.

When the slip segments or members 28 are moved upwardly with respect to the mandrel, the rear inclined surfaces 29 of the segments contact with the expanding surfaces 25 of the mandrel and move the slips outwardly, whereby gripping teeth 28a on the external surface of the slip segments may engage the wall of the outer casing 11. The slip segments or members are constantly urged toward an upper position with respect to the mandrel by a coiled spring 34 which surrounds the mandrel beneath the slip segments. The coiled spring is confined within a sleeve 35 which sleeve is slidable on the mandrel. The lower end of the spring engages a follower ring 36 which rests upon the upper end of the lower coupling member 22. It will be apparent that the coil spring 34 constantly exerts its pressure in a direction tending to move the slip segments or members 28 upwardly with respect to the expanding surfaces 25 of the mandrel.

For restraining the slip segments against upward movement on the mandrel to hold said slips against movement into a set position, a retaining collar 37 engages the upper end of the slip segments. The upper portion of the collar encircles the lower portion of an annular piston 38 and is connected to said piston, as well as to the mandrel by means of a plurality of shear pins 39. Obviously, with the restraining collar 37 in engagement with the upper end of the slip segments, as shown in Figure 2, and with said collar fastened to the mandrel by the shear pins 39, the slip segments 28 are restrained against upward movement with respect to said mandrel.

The piston 38 which is mounted between the restraining collar 37 and the mandrel is slidable on the reduced portion 26 of said mandrel and has its upper end enlarged and encircling the upper reduced portion 26 of said mandrel. This upper enlarged end of the piston is formed with an annular recess or seat 40 within which the lower portion of an annular sealing element 41 is mounted. Suitable screws 42 fasten the sealing member 41 to the piston. The sealing member is constructed of rubber or other deformable material and includes an inner lip 41a which engages the surface 27 of the mandrel and an outer lip 41b which is adapted to engage the wall of the outer casing 11 as the device is lowered therethrough. For limiting the upward travel of the piston 38 on the mandrel after the shear pins 39 have been fractured, said piston is formed with a plurality of slots 43 within which screws 44 extend; the screws are threaded into the mandrel and have their outer portions disposed within said slots. For receiving the fractured shear pins 39 after said shear pins are broken, the outer surface of the piston 38 is formed with vertically extending recesses 45, each recess being in alignment with one of the shear pins (Figure 6).

In the operation of the device, the parts are assembled as shown in Figure 2 with the slip segments or members 28 being in their lowered or retracted position with respect to the expanding surfaces 25 of the mandrel. The segments are locked in this lowered position by means of the restraining collar 37 which, as explained, is fastened to the mandrel by the shear pins 39. The lower end of the piston 38 is also connected to the shear pin between the collar 37 and the mandrel

and at this time, the coiled spring 34 beneath the slip segments is in its compressed position.

The device is assembled in the inner casing or pipe string 14 by means of the coupling collars 22 and is lowered with the inner string through the outer casing 14. During such lowering, circulation downwardly through the inner string and upwardly through the annular space between the inner and outer strings is possible, for obviously, upward circulation through the annular space will merely by-pass the outer lip seal 41b. It is noted that the external diameter of the guide wings 23 of the coupling collars 22 is slightly larger than the outer diameter of the retracted slip segments 28, whereby said wings prevent the teeth of said slip segments from striking or engaging the inner surface or bore of the casing 11 as the device is being lowered therethrough.

When it is desired to set the device, it is only necessary to reverse circulation and pump fluid downwardly through the annular space between the pipe strings 11 and 14. This fluid pressure will act upon the annular sealing element 41 and will urge the piston 38 downwardly. When the pressure reaches a point sufficient to fracture the shear pins 39, said piston 38 moves downwardly into engagement with the shoulder 27 on the exterior of the mandrel which limits downward movement of the piston. Upon fracturing of the shear pins 39, the coil spring 34 acting below the slip segments 28 will immediately move said slip segments upwardly on the expanding surfaces 25 of the mandrel whereby the teeth 28a of said slips are moved into gripping engagement with the inner wall of the outer casing 11. As the slips move upwardly to an expanded position, the restraining collar 37, which is now disconnected from the piston 38 slides upwardly with respect thereto, and the inner fractured ends of the shear pins 39 move upwardly within the recesses 45 which are provided for this purpose in the outer surface of the piston. After the slips are set it will be evident that the weight of the inner string 14 will be transferred through the slips directly to the outer casing 11 and said outer casing will function to transfer the load directly to the competent formation B. After the pins 39 have been fractured, upward movement of the piston 38 and its sealing element 41 is limited by the limit screws 44 which ride within the slots 43 in the piston.

From the foregoing, it will be seen that a simple and efficient hanger device is provided for supporting an inner pipe or casing string within an outer pipe or casing. Because the slips are restrained from moving into an operating position until such time as sufficient fluid pressure is applied to the sealing element 41 and its piston, the device may be selectively set at any desired location within the outer casing. Also, actuation is effected without the necessity of rotating or otherwise manipulating the inner pipe string to which the device is attached. So long as the weight of the inner string is imposed upon the slip segments or members, the same will be maintained in their expanded or set position because of the coaction between the expanding surfaces 25 of the mandrel and the inner surfaces of the slip segments. If it ever becomes necessary to remove the device, an upward movement of the pipe would tend to cause the expanding surfaces 25 of the mandrel to move in a direction with respect to the slips which

would allow said slips to be released from gripping engagement with the outer casing. The device operates entirely within the annulus between the two pipe strings and at all times allows an upward flow through the annulus even after the slip segments have been moved to an engaged or gripping position. The device is positively locked against actuation during its lowering and the coil spring 34 cannot function to move the slip segments into gripping position until a sufficient pressure has been applied to the piston to fracture the shear pins 39 and thereby release the restraining collar 37.

The foregoing description of the invention is explanatory thereof and various changes in the size, shape and materials, as well as in the details of the illustrated construction may be made, within the scope of the appended claims, without departing from the spirit of the invention.

Having described the invention, I claim:

1. A hanger device for supporting a string of well pipe including a tubular mandrel defining with first and second ends thereof threaded means for connecting same into a string of pipe and defining an internal longitudinal passageway adapted to allow flow of fluid therethrough in either direction, a plurality of segmental gripping slips mounted on said mandrel and adapted to be expanded outwardly into gripping position upon a longitudinal movement of the slips relative to the mandrel, a coiled spring surrounding the mandrel beneath the gripping slips and urging said slips upwardly on said mandrel toward their expanded position, a restraining collar encircling the mandrel and engaging the upper end of the slips to maintain the same in a lowered position against compression of the spring, and a shear pin connecting the collar to the mandrel in a position holding the slips against actuation, whereby the coiled spring cannot function to expand said slips until said shear pin is fractured.

2. A hanger device for supporting a string of well pipe including a tubular mandrel defining with first and second ends thereof external threads for connecting same into a string of pipe and defining an internal longitudinal passageway adapted to allow flow of fluid therethrough in either direction, a plurality of segmental gripping slips mounted on said mandrel and adapted to be expanded outwardly into gripping position upon a longitudinal movement of the slips relative to the mandrel, a coiled spring surrounding the mandrel beneath the gripping slips and urging said slips upwardly on said mandrel toward their expanded position, a restraining collar encircling the mandrel and engaging the

upper end of the slips to maintain the same in a lowered position against compression of the spring, a shear pin connecting the collar to the mandrel in a position holding the slips against actuation, whereby the coiled spring cannot function to expand said slips until said shear pin is fractured, and an annular piston slidably mounted on the mandrel above the restraining collar and adapted to fracture said shear pin upon downward movement of the collar, with respect to the mandrel, said piston being hydraulically actuated to fracture said pin and thereby release the slips for actuation.

3. A hanger device as set forth in claim 2, wherein the piston includes an annular lip-type sealing member which will allow flow upwardly thereby but will be actuated by a downward pressure exerted thereagainst.

4. A hanger device for supporting a string of well pipe including a tubular mandrel defining with first and second ends thereof threaded means for connecting same into a string of pipe and defining an internal longitudinal passageway adapted to allow flow of fluid therethrough in either direction, a plurality of segmental gripping slips mounted on said mandrel and adapted to be expanded outwardly into gripping position upon a longitudinal movement of the slips relative to the mandrel, spring means mounted on the exterior of the mandrel below the slips engaging a lower end of said slips and urging the slips upwardly on said mandrel toward a gripping position, a restraining collar encircling the mandrel and engaging an upper end of the slips to maintain the same in a lowered position against compression of the spring, and a shear pin connecting the collar to the mandrel in a position holding the slips against actuation, whereby the spring cannot function to expand said slips until said shear pin is fractured.
